United States Patent Office

Des. 196,432
Patented Oct. 1, 1963

196,432

SHAVER

Carl W. Sundberg, Bloomfield Hills, and Montgomery
Ferar, Huntington Woods, Mich., assignors to Sperry
Rand Corporation, New York, N.Y., a corporation of
Delaware

Filed Jan. 14, 1963, Ser. No. 73,166

Term of patent 14 years

(Cl. D22—3)

FIG. 2

FIG. 1

FIG. 3

FIG. 4

FIG. 5

FIG. 6

FIG. 1 is a front elevation of a shaver showing our new design;

FIG. 2 is a top view thereof;

FIG. 3 is a bottom view thereof;

FIG. 4 is a side elevation as seen from the left of FIG. 1;

FIG. 5 is a side elevation as seen from the right of FIG. 1; and

FIG. 6 is a rear elevation thereof.

The essential features of the design reside in the portions shown in solid lines on the drawings.

We claim:

The ornamental design for a shaver, substantially as shown and described.
